UNITED STATES PATENT OFFICE.

THOMAS I. RANKIN, OF PHILADELPHIA, PENNSYLVANIA, ASSIGNOR TO THE
ABRAM COX STOVE COMPANY, OF SAME PLACE.

DESIGN FOR A FURNACE-FRONT.

SPECIFICATION forming part of Design No. 22,572, dated June 27, 1893.

Application filed March 2, 1893. Serial No. 464,457. Term of patent 7 years.

To all whom it may concern:

Be it known that I, THOMAS I. RANKIN, a citizen of the United States, residing in Philadelphia, Pennsylvania, have invented a new 5 and original Design for a Furnace-Front, of which the following is a specification.

My design for a heating furnace front is clearly shown in the accompanying drawings, in which—

10 Figure 1, is a face view. Fig. 2, is a vertical sectional view on the line 1—2, Fig. 1. Fig. 3, is a transverse sectional view on the line 3—4, Fig. 1.

15 The essential features of the design are the overhanging ornamental top, the ornamentation of the doors, and the ornamentation of the framing around the front.

20 The frame A consists of a series of ornamental rounded rims a , extending from an outer edge a' to the main portion B of the front; on the upper border of the frame is a center piece a^2 .

25 The main portion B of the front has an overhanging panel D above the fire door, and this panel extends nearly to the outer face of the frame A, as shown by dotted lines in Fig.

30 3. The ornamentation of this panel consists of two S-scrolls at each side, with rosettes in the four corners, and a center piece consisting of a series of rounded leaves extending from the central point of the base and sur-

rounded by a border or frame; between the border and the S-scrolls are ornamental knobs.

35 The fire door is ornamented by two S-scrolls and knobs on each side of the circular damper. On each side of the damper E is a rosette, and the ash pit door is also ornamented with scrolls and knobs, in keeping with the rest of the design. 40

I claim—

1. The design for a furnace front as herein described and shown.

2. In the design for a furnace front, the body provided, with an ornamental panel projecting beyond the line of the flat portion and curved at its upper edge, as described and shown. 45

3. In the design for a furnace front the design for the fire door of a furnace, as herein shown and described. 50

4. In the design for a furnace front the design for the ash pit door of a furnace, as herein described and shown.

55 In testimony whereof I have signed my name to this specification in the presence of two subscribing witnesses.

THOMAS I. RANKIN.
